UNITED STATES PATENT OFFICE.

CORNELIUS B. CORCORAN, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,045,374.

Specification of Letters Patent.

Patented Nov. 26, 1912.

Application filed October 6, 1911. Serial No. 653,118.

To all whom it may concern:

Be it known that I, CORNELIUS B. CORCORAN, a citizen of the United States, residing in borough of Bronx, city of New York, in the county of New York and State of New York, have invented certain new and useful Improvements in Type-Writing Machines, of which the following is a specification.

- 10 This invention relates to the mechanism in a front strike typewriting machine, by which the ribbon is vibrated to cover and uncover the printing point at every type stroke.
- 15 In the patent to F. A. Cook, No. 926,050, dated June 22, 1909, a bichrome ribbon mechanism is shown in connection with a device for rendering the ribbon inoperative, so that the types may strike directly on the 20 paper, as is desirable in writing stencils. In said patent, the vibrating lever for the ribbon carrier is engaged by an actuator which is operated by the universal bar frame at each type stroke. This actuator is shiftable 25 so that slots thereon may engage with one or the other of wrist pins set on said lever at variable distances from its fulcrum, and thus impart a variable throw to the ribbon. This device can be so set as to bring the 30 top or the bottom of the ribbon between the type and the paper at will, and thus from a striped ribbon more than one color of writing can be written. Also means are provided for disengaging the lever from said 35 actuator, to render the ribbon inoperative even though the type is struck. This vibrating lever is fulcrumed on a bracket connected with the platen shift rail; for shifting the ribbon bodily with the platen when 40 writing with the upper case types. Whether the ribbon is operative or is inoperative, as in writing stencils, said lever and ribbon carrier always move bodily with the platen when the latter is shifted, since the lever 45 fulcrum is fast to the platen shift rail. The fulcrum is positively returned to normal position, but the lever returns by its own weight, so slight causes, like a bend in the carrier, or dust getting into the carrier, are liable to prevent the lever from returning 50 promptly to normal position. It therefore may swing on its pivot when being lowered, and hence possibly cause the ribbon to cover the printing point, and interfere with sten-

cil writing when the lower case types strike 55 the platen. My invention is designed to prevent the lever from remaining raised when the platen is lowered.

In the form of my invention herein illustrated, I have provided a projection at the 60 upper rear end of the vibrating lever which, when the actuator is disengaged, is disposed close to a guide thereon, so that when the lever is shifted with the platen, said projection bears against said guide, and said lever 65 is prevented from turning about its fulcrum. The ribbon carrier is therefore moved positively with the platen when the latter is shifted.

In the accompanying drawings, Figure 1 70 is a sectional view of an Underwood front strike typewriting machine, showing my invention as applied thereto. Fig. 2 is a detail view of the principal parts of my invention. Fig. 3 shows the vibrator lever as 75 locked when my invention is applied. Fig. 4 shows the vibrator lever in its normal position when raising the ribbon in ordinary writing.

Keys 1 of the typewriter depress levers 2 80 to move bell cranks 3 to raise type bars 4 causing types 5 and 6 to strike against the front of a platen 7 carried on a platen frame 8. Said platen frame is pivotally mounted at 9 on a carriage 10, which travels on rails 85 11 and 12 in the ordinary letter-feeding movement, operated by a universal bar 13.

The platen 7 is shiftable by means of a key 14 acting through a lever 15 and bell crank 16, the latter supporting a shift rail 90 17. This shift rail bears against a roll 18 mounted on the platen frame 8, and so may cause said frame to be raised at will.

Universal bar 13 is pivoted at 19 on the frame and is actuated by heels 20 of the 95 type bars 4, at every depression of any type key.

On the platen shift rail is pivotally mounted at 21, a vibrator lever 22, to operate a ribbon carrier or vibrator 23 to raise 100 the ribbon in front of the platen every time a type key is depressed. The vibrator lever 22 is moved by an upstanding wall 24 on the universal frame, on which are wings comprising slots 25 and 26 adapted to engage pins 27 and 28 on the vibrator lever 22. 105

Every time the universal bar is reciprocated, one of the pins 27 or 28 engages the

wings and is moved back, thus raising the vibrator lever 22 and lifting the ribbon. An actuator 29 comprising spaced arms embracing wall 24 is provided on the upstanding wall 24, having sides or wings 30 in which are formed said slots 25 and 26, and the actuator may be shifted so as to cause either of said slots to engage with its adjacent pin and thus determine the amount of throw given the ribbon. It will be seen that if pin 28 is engaged, the vibrator 23 will be given a small throw because said pin is distant from the fulcrum 21. This brings only the upper edge of the ribbon between the type and the platen. This is usually black.

If pin 28 is engaged, the vibrator will be given a long throw, because said pin is adjacent to the fulcrum. This brings the lower edge of the ribbon (usually red) into operation. It will also be seen that the actuator 29 may occupy an intermediate position in which it engages neither of said pins, and the ribbon will not be vibrated, as in writing stencils.

25. A link 31 is provided for shifting actuator 29 by means of an arm 32 on a shaft 33, which may be turned by keys 34. A lock 35 is also provided for holding said shaft so that the actuator 29 will be in its inoperative position.

30. On the upper end 36 of lever 22 near pins 27 and 28, is provided an arm or projection 37 for coöperating with a guide, which is in the form of a panel 38. This part 38 is opposite said arm 37 when the actuator 29 is at its middle or inoperative position, so that the vibrator 23 is positively held down during the operation of cutting a stencil, no matter what position the platen shift rail 17 may be placed in.

35. Openings 39 and 40 are provided for permitting full throw of arm 37 of vibrator lever 22, whenever actuator 29 is so set as to engage with either pin on said vibrator, and 45 a corresponding opening 41 is provided in the wall 24.

The positive locking of vibrator 23 by my improvement is shown in Fig. 3, where the platen rail has been raised above normal position; the arm bears against the panel, and the vibrator cannot possibly swing upward. In Fig. 4, is illustrated the usual throw of the vibrator permitted in writing red.

50. Variations may be resorted to within the scope of the invention.

Having thus described my invention, I claim:

1. In a typewriting machine, the combination of a shiftable platen, a universal bar, means moving with said shiftable platen for vibrating the ribbon at the key strokes by said universal bar, means for disconnecting said universal bar, and means for compelling said vibrating means to preserve its nor-

mally inoperative position when moving with said platen during the disconnection of the universal bar.

2. In a typewriting machine, the combination with a ribbon vibrating mechanism, a universal bar for operating it, and means for disconnecting said mechanism from said bar for rendering the vibrating mechanism inoperative, of a shiftable platen, a bar shifting with the platen carrying a member of said ribbon-vibrating mechanism, and means to compel said member to maintain its inoperative position when shifting with the platen.

3. In a typewriting machine, the combination of a shiftable platen, a bar shifting said platen, a ribbon vibrator pivoted on said bar, means for actuating the vibrator, and shiftable means for silencing the vibrator, a guide, and a member on the vibrator to coöperate with said guide to hold the vibrator positively inoperative.

4. In a typewriting machine, the combination with a shiftable platen and a universal bar, of a ribbon vibrator lever moving with said platen, an actuator moved by said universal bar for operating said lever, shiftable means for silencing said lever, of an arm or rest on said lever, and a coöperating guide on said actuator to hold said lever positively inoperative during the shifting of the platen.

5. In a typewriting machine, the combination of a shiftable platen, a ribbon vibrator lever moving with said platen, pins on said lever, an actuator having slots to engage said pins, means for shifting said actuator to engage either of said pins or to occupy a position free from said pins, an arm or rest on the lever, and a coöperating guide on the actuator to hold said lever when free from said pins.

6. In a typewriting machine, the combination of a shiftable platen, a ribbon vibrator lever moving with said platen, pins on said lever, an actuator having slots to engage said pins, means for shifting said actuator to engage either of said pins or to occupy a position free from said pins, an arm or rest on the lever, and a coöperating guide on the actuator to hold said lever when free from said pins; slots or openings being provided in said actuator to accommodate said arm or rest when said pins engage said actuator.

7. In a typewriting machine, the combination of a shiftable platen, a universal bar, a ribbon vibrator lever moving with the shiftable platen and vibrated from the universal bar through an actuator, pins on said lever to engage said actuator, slots in said actuator to engage said pins, means for shifting said actuator to engage either of said pins or to be free from them, an arm or rest on the lever to coöperate with a guide on

the actuator to hold said lever to keep the ribbon inoperative when the platen is shifted, and a key controlling the means for shifting the actuator.

- 5 8. In a typewriting machine, the combination of type keys operating a universal frame, a shifttable platen, a ribbon vibrator lever moving with said platen, an actuator on the universal frame, slots in said actuator, pins on said lever to coöperate with said slots to vibrate said lever, a key to shift said actuator to engage with either of said pins or to be free from said pins, an arm on said lever, and a panel on said actuator to coöperate with said arm to hold said ribbon lever to keep the ribbon positively inoperative when free from said pins, openings being provided in said actuator to permit said abutment to move freely when said pins engage with said slots.
- 10 9. In a typewriting machine, the combination of type keys operating a universal frame, a shifttable platen, a ribbon vibrator lever moving with said platen, an actuator on the universal frame, slots in said actuator, pins on said lever to coöperate with said slots to vibrate said lever, a key to shift said actuator to engage with either of said pins or to be free from said pins, an arm on said lever, and a panel on said actuator to coöperate with said arm to hold said ribbon lever to keep the ribbon positively inoperative when free from said pins, openings being provided in said actuator to permit said abutment to move freely when said pins engage with said slots.

15 10. In a typewriting machine, the combination of type keys operating a universal frame, a shifttable platen, a ribbon vibrator lever moving with said platen, an actuator on the universal frame, slots in said actuator, pins on said lever to coöperate with said slots to vibrate said lever, a key to shift said actuator to engage with either of said pins or to be free from said pins, an arm on said lever, and a panel on said actuator to coöperate with said arm to hold said ribbon lever to keep the ribbon positively inoperative when free from said pins, openings being provided in said actuator to permit said abutment to move freely when said pins engage with said slots to vibrate said lever, a key to shift said actuator to engage with either of said pins or to be free from said pins, an arm on said lever, and a panel on said actuator to coöperate with said arm to hold said ribbon lever to keep the ribbon positively inoperative when free from said pins, openings being provided in said actuator to permit said abutment to move freely when said pins engage with said slots.

20 11. In a typewriting machine, the combination of type keys operating a universal frame, a shifttable platen, a ribbon vibrator lever moving with said platen, an actuator on the universal frame, slots in said actuator, pins on said lever to coöperate with said slots to vibrate said lever, a key to shift said actuator to engage with either of said pins or to be free from said pins, an arm on said lever, and a panel on said actuator to coöperate with said arm to hold said ribbon lever to keep the ribbon positively inoperative when free from said pins, openings being provided in said actuator to permit said abutment to move freely when said pins engage with said slots.

25 12. In a typewriting machine, the combination of type keys operating a universal frame, a shifttable platen, a ribbon vibrator lever moving with said platen, an actuator on the universal frame, slots in said actuator, pins on said lever to coöperate with said slots to vibrate said lever, a key to shift said actuator to engage with either of said pins or to be free from said pins, an arm on said lever, and a panel on said actuator to coöperate with said arm to hold said ribbon lever to keep the ribbon positively inoperative when free from said pins, openings being provided in said actuator to permit said abutment to move freely when said pins engage with said slots.

30 13. In a typewriting machine, the combination of type keys operating a universal frame, a shifttable platen, a ribbon vibrator lever moving with said platen, an actuator on the universal frame, slots in said actuator, pins on said lever to coöperate with said slots to vibrate said lever, a key to shift said actuator to engage with either of said pins or to be free from said pins, an arm on said lever, and a panel on said actuator to coöperate with said arm to hold said ribbon lever to keep the ribbon positively inoperative when free from said pins, openings being provided in said actuator to permit said abutment to move freely when said pins engage with said slots.

35 14. In a typewriting machine, the combination of type keys operating a universal frame, a shifttable platen, a ribbon vibrator lever moving with said platen, an actuator on the universal frame, slots in said actuator, pins on said lever to coöperate with said slots to vibrate said lever, a key to shift said actuator to engage with either of said pins or to be free from said pins, an arm on said lever, and a panel on said actuator to coöperate with said arm to hold said ribbon lever to keep the ribbon positively inoperative when free from said pins, openings being provided in said actuator to permit said abutment to move freely when said pins engage with said slots.
